UNITED STATES PATENT OFFICE.

JOHN REGAN, OF NEW BEDFORD, MASSACHUSETTS, ASSIGNOR TO CROMPTON & KNOWLES LOOM WORKS, OF WORCESTER, MASSACHUSETTS, A CORPORATION OF MASSACHUSETTS.

STOPPING MECHANISM FOR KNITTING MACHINES.

Application filed July 27, 1925. Serial No. 46,218.

This invention relates to a stopping mechanism for a knitting machine and particularly to mechanism for preventing the machine from turning backward.

5 It has been found that a knitting machine when stopped automatically frequently turns backward a sufficient amount to unthread certain of the hooks. This backward movement may be occasioned by different causes 10 such as the relative positions of certain unbalanced parts of the machine at the instant of stopping.

After the machine has stopped and turned backward to an extent, sufficient to unthread 15 any of the hooks, a serious defect is caused in the fabric when the machine is again started in operation.

It is the object of my invention to provide 20 mechanism for automatically stopping a knitting machine and for preventing backward movement of the machine when thus stopped.

My invention further relates to arrangement and combinations of parts which will 25 be hereinafter described and more particularly pointed out in the appended claims.

A preferred form of the invention is shown in the drawings in which

Fig. 1 is an end elevation of parts of a 30 knitting machine embodying my invention;

Fig. 2 is a detail sectional plan view, taken along the line 2—2 in Fig. 1;

Fig. 3 is a partial front elevation, looking in the direction of the arrow 3 in Fig. 1;

35 Fig. 4 is a sectional side elevation, taken along the line 4—4 in Fig. 3;

Figs. 5 and 6 are views similar to Fig. 3 but showing the parts in different positions; and

40 Figs. 7 and 8 are views similar to Fig. 4 and taken along the lines 7—7 and 8—8 in Figs. 5 and 6 respectively.

Referring particularly to Fig. 1, I have shown portions of a knitting machine com-

45 prising a frame 10, yarn rolls 11, tension or whip rolls 12 and knitting mechanism indicated generally by the letter M. The machine is provided with a pair of bottom shafts 13 and 14 connected by gears 15 and 16 and driven by a pinion 17 meshing with the gear 15 on the shaft 13. The pinion 17 is mounted upon a drive shaft 18 and the rotation thereof is controlled through connections (not shown) from a shipper rod

20. The rod 20 is slidable in bearings 21 and 55 22 on the frame 10 and is provided with a fork 23 engaged by an arm 24 (Fig. 2) which may be swung manually by a handle (not shown).

The parts thus far described are of the 60 usual type and in themselves form no part of my present invention. A cam 25 (Figs. 3 and 4) on the shaft 18 acts through a lever 26 and link 27 (Fig. 1) to actuate the stop motion which is fully described and claimed 65 in my prior application, Serial No. 572,208, filed November 25, 1924.

For the purposes of this application it is sufficient to state that an arm 30 shown in dotted lines in Fig. 1 is swung upward whenever the stop motion acts to bring the machine to rest. This arm 30 is connected by a link 31 to a latch 32 which engages a collar 33 (Fig. 3) which forms a part of a sleeve 34 which is slidable on the rod 20 and which supports a coil spring 35 interposed between the collar 33 and the machine frame 10.

The outer face of the collar 33 engages a collar 36 fast to the shipper rod 20 and provided with an offset and downwardly inclined finger 37. The collar 36 is preferably cut away as indicated at 38 (Fig. 6) to clear the latch 32.

A ratchet wheel 40 is fixed on the shaft 85 18 and is engaged by a pair of holding pawls 41 and 42. The pawl 41 is provided with a rod 43 which is bent rearwardly to form a hook which engages the finger 37 as indicated in Figs. 3 and 4.

The pawl 42 is provided with a flange or 90 projection 45 overlying a portion of the pawl 41 so that when the pawl 41 is raised it will carry with it the pawl 42. The pawls 41 and 42 are of such lengths that they form a half-tooth spacing for the teeth of the 95 ratchet wheel 40. The latch 32 is pivoted upon a fixed bracket 46 secured to the frame 10.

The normal running position of the parts 100 is as shown in Figs. 3 and 4, with the latch 100 32 engaging and holding the collar 33, and with the spring 35 in compression. The shipper rod 20 is in its right hand or running position and the finger 37 on the collar 36 projects under the hook 43 and holds the 105 pawls 41 and 42 in raised or inoperative position as clearly shown in Fig. 4.

In Figs. 5 and 7 I have indicated the re-

lation of the parts when the machine is stopped by hand. In this case the shipper rod 20 is moved to the left, sliding freely through the collar 33 in the sleeve 34 which parts are retained in their normal position by the latch 32. This movement of the shipper rod, however, carries the collar 36 to the left, thus withdrawing the finger 37 sufficiently to permit the pawls 41 and 42 to engage the ratchet wheels 40 and prevent backward movement of the shaft 18.

In Figs. 6 and 8, I have indicated the operation when the machine is stopped automatically. In this case the arm 30 (Fig. 1) is swung upward, acting through the link 31 to raise the latch 32 and release the collar 33. The spring 35 then acts to force the collar to the left, carrying with it the collar 36 on the shipper rod 20 and thus again withdrawing the finger 37 and permitting the pawls 41 and 42 to engage and hold the ratchet wheel 40.

I have thus provided exceedingly simple mechanism by which the knitting machine will be held from backward movement when the machine is stopped either manually or automatically, and at the same time I avoid excessive wear of the pawls by holding them out of operation during the normal running of the machine.

Having thus described my invention and the advantages thereof, I do not wish to be

limited to the details herein disclosed, otherwise than as set forth in the claims, but what I claim is:—

1. In a knitting machine, a reverse locking mechanism comprising a normally inoperative holding device, and means to render said holding device operative to prevent rearward movement of the machine as said machine is about to be stopped, said holding device comprising a ratchet wheel, a holding pawl, a sliding rod, a pawl-controlling finger mounted on said rod, a spring-pressed actuating device for said sliding rod, and automatically controlled means for holding and releasing said actuating device.

2. In a knitting machine, a reverse locking mechanism comprising a normally inoperative holding device, and means to render said holding device operative to prevent rearward movement of the machine as said machine is about to be stopped, said holding device comprising a ratchet wheel, a holding pawl, a sliding rod, a finger mounted on said rod and normally holding said pawl in raised inoperative position, a spring-pressed actuating device for said sliding rod, a latch for said actuating device, and a connection through which said latch is raised as said machine is about to be stopped automatically.

In testimony whereof I have hereunto affixed my signature.

JOHN REGAN.
